(57) **CLAIM**

The ornamental design for a ceiling fan blade bracket assembly, as shown and described.

DESCRIPTION

FIG. 1 is a perspective view of the ceiling fan blade bracket assembly showing my new design;

FIG. 2 is a side elevational view thereof;

FIG. 3 is a top plan view thereof; and,

FIG. 4 is a bottom plan view thereof.

Broken lines illustrate portions of the ceiling fan blade bracket assembly that form no part of the claimed design.
